UNITED STATES PATENT OFFICE.

ROBERT M. KEATING, OF MIDDLETOWN, CONNECTICUT.

DESIGN FOR A BASE AND SHAFT SUPPORT FOR GASOLENE-ENGINES.

SPECIFICATION forming part of Design No. 34,110, dated February 19, 1901.

Application filed January 18, 1901. Serial No. 43,818. Term of patent 7 years.

To all whom it may concern:

Be it known that I, ROBERT M. KEATING, residing at Middletown, in the county of Middlesex and State of Connecticut, have invented a certain new and useful Design for a Base and Shaft Support for Gasolene-Engines, of which the following is a specification, reference being had therein to the accompanying drawings.

10 This invention is a design for a base and shaft support for a gasolene-engine.

Figure 1 is an elevation of one side of the base and support, and Fig. 2 is a reverse view of the same.

15 The upper portion of the base is on a straight line *a*, from which line *a* the straight edges *b b* extend to the intersection of the nearly cylindrical motor-case *c*, which case has a flat face *d* and a central perforation *f*, substantially as shown. The wheel-case *c* at one side departs from the cylindrical form, and the projection *e* produces what may be called a "pear shape," taken in connection with the cylindrical portion *c c c*, the protuberance *a b b* being at about a right angle from the protuberance *e*. The protuberance *e* has a round

perforation *g*. The wheel-case is nearly cylindrical, struck from the center of the opening *g*, and having its flat face *h* on the plane parallel with the plane face *d*, but not the same plane, the protuberance *e* being a projection from the flat or plane face *h*. A reverse view shows the nearly cylindrical case with its flat face *h* surrounding the opening *g* and having the rim *k* extending nearly around the circle, but merging into the smaller curved rim *l*, which is concentric with opening *f*. The curved rim *l* thus projects from the flat face *d'* of the motor-case, which is opposite to and parallel with the flat face *d* of the motor-case. Near the flat edge *a* there is a curved projection *o*.

What I claim, and desire to secure by Letters Patent, is—

The design for a base and shaft support for gasolene-engines, as shown and described.

In testimony whereof I affix my signature in presence of two witnesses.

ROBERT M. KEATING.
